BLEACHING APPARATUS.

1,167,728.

Specification of Letters Patent.

Patented Jan. 11, 1916.

Application filed February 16, 1915. Serial No. 8,490.

To all whom it may concern:

Be it known that I, FLOYD G. TEN BROECK, a citizen of the United States, and resident of the borough of Brooklyn, county of 5 Kings, city and State of New York, have made a certain new and useful Invention Relating to Bleaching Apparatus, of which the following is a specification, taken in connection with the accompanying drawing, 10 which forms part of the same.

This invention relates especially to apparatus for bleaching fibrous material for use in textile or paper manufacture, such for example as wood pulp, and is adapted to 15 bleach such material when containing so little water as to be in a substantially non-fluent or plastic condition. For this purpose one or more large elongated rotary bleachers are used each adapted to hold a charge 20 amounting to many tons of the material and feed it slowly through the bleacher by the combined effect of its slow rotation and slight inclination. The bleacher may be divided into several chambers by spaced parti- 25 tions and these chambers may be provided with suitable mixing and agitating means or projections such as ribs projecting inward from the wall of the bleacher which are preferably so formed as to give it more 30 energetic agitating and mixing action adjacent the feed end of the cylindrical unit. The bleacher may also, if desired, be formed with a reduced diameter mixing feed chamber axially mounted on the feed end of the 35 bleacher and provided with a rotary beater and feeder to thoroughly mix and incorporate the bleach and fibrous material and feed it into the bleacher itself through which it gradually passes and is at the same time 40 sufficiently agitated or mixed so as to minimize undesirable localized action on any part of the material. If desired part of the bleach may be incorporated with the pulp in the first instance and the mixture 45 fed through one of these rotary bleachers and then the material discharged into a washer to thoroughly eliminate the reaction products from the pulp which can then be incorporated with a second charge of bleach 50 and similarly pass through a second rotary bleacher which may with advantage be oppositely inclined and arranged alongside or adjacent the first so that the bleached pulp may be discharged adjacent the feed end of 55 the first bleacher.

In the accompanying drawings showing in a somewhat diagrammatic way an illustrative embodiment of this invention, Figure 1 is an elevation, parts being shown in section. Fig. 2 is a transverse section along 60 the line 2—2 of Fig. 1. Fig. 3 is a similar section along the line 3—3.

The elongated rotary bleacher which may be of any suitable construction may have a length of 100 to 200 feet more or less and a 65 diameter of 8 to 10 or 15 feet or so, so that it will hold and handle a charge of many tons of the thick mixture of fibrous material and bleach which may of course be any desired bleaching composition such as the 70 usual chlorinated lime or the like. The bleacher is preferably mounted at a slight inclination which promotes the desired gradual feed of the material therethrough when it is slowly rotated by any suitable 75 means and this may be further regulated by forming internal feeding or feed regulating devices throughout or at intervals along the interior of the bleacher. The bleacher may be conveniently constructed in the same general manner as the large rotary kilns which are used in the Portland cement industry and as indicated in the drawing the bleacher may have the substantially cylindrical shell 80 30 of sheet steel or the like to which are 85 secured at intervals along its length suitable tires 37, each of which may be supported on two or more bearing rolls 28 mounted in bearing blocks, such as 29. For rotating the bleacher a crown gear 32 may be conveniently secured to the shell and slowly rotated by a suitable drive gearing such as 34 90 operated from any desired source of power.

The bleacher may be provided with a substantially inert lining 9 of brickwork, cement concrete, or the like, which for a shell ten feet or so in diameter may have a thickness of some 4 to 6 inches and be provided with integral or otherwise formed partitions, such as 12, 15, having restricted axial passages 13, 16 therethrough of the desired size so as to form a series of bleacher chambers between these partitions. Suitable agitating and mixing devices such as ribs or projections of various forms may be provided in 100 the inside of the bleacher especially adjacent its feed end to insure the desired agitation or mixing of the charge, and if desired, suitable positively lifting or bucket ribs, such as 11, may be formed in this agitating 110

mixing chamber as by securing these heavy metal ribs to the bleacher shell or otherwise securely mounting them in position, see Fig. 2. Other forms of agitating devices may be used at various parts of the bleacher, such for example, as the substantially radial agitating ribs 14 shown in Fig. 3 which may be secured in or formed integral with the lining 9 and project into the interior of the bleacher to the desired extent. These ribs may, of course, be of different effective heights at various parts of the bleacher and a smaller number of agitating ribs 18 which project a less distance into the bleacher chamber are shown adjacent its discharge end. If desired also more positive feeding devices may be used to insure the definite feeding of the charge through the bleacher at any desired points, such, for example, as the spiral feeding ribs 17 which may be secured to the shell or lining and project any desired distance into the bleacher so as to promote the forward movement of the charge in proportion to the pitch of these ribs which may extend continuously a number of times around the bleacher or extend only part way around as desired.

The charge of wood pulp or other fibrous material and bleach may be mixed and fed into the bleacher in any desired way preferably in a substantially non-fluent or plastic condition as when the mixture contains some 15 to 25 percent. or so of pulp and has a somewhat doughy consistency. If desired, a mixing feeding device may be secured directly to the bleacher and may be given the form of the reduced diameter mixing feed chamber 3 which may be axially secured to the feed end of the bleacher and have a slip joint connection 10 with the stationary receiving or feed hopper 2. The feeder 4 may be mounted in this feed chamber and rotated preferably in the same direction as the direction of the rotation of the main bleacher by the drive pulley or device 6 on the shaft beyond the bearing 5 in the hopper so that the helical beater blades have a positive feeding action to mix and force the material into the first chamber of the bleacher, a suitable spreader or deflector being if desired used at this point, such for instance as the conical deflector 7, which may be mounted on the end of the beater so as to deflect the entering material toward the conical lining 8 which is advantageous for some purposes.

The unbleached pulp may be fed into the hopper 2 and the solution of hypo-chlorite of lime or other bleach may be simultaneously supplied to the hopper as through the bleach pipe 1, the material being engaged by the beater and thoroughly and preferably substantially uniformly incorporated before being fed into the first chamber of the main bleacher. In regular practice, it seems de-

sirable to have the charge remain a number of hours in such a bleacher and the time of treatment is regulated by the speed at which the elongated rotary bleacher is operated and by its inclination and the character of the feeding and feed regulating devices therein, a number of hours' bleaching treatment of this character being desirable in effecting the gradual bleaching of the pulp and thus minimizing the chance of injury and this makes it unnecessary to use high bleaching temperatures which is a further advantage as is also the exclusion of light during the bleaching operation. The bleached material may be finally discharged from the bleacher as through a restricted discharge passage 19 which may be in the form of a discharge flange as indicated and thereafter the bleached pulp or other material may be given any desired subsequent treatment.

In bleaching wood pulp it is for some purposes desirable to effect the bleaching in several stages and to thoroughly eliminate the reaction products from the partly bleached material so as to minimize any staining action that they might have on the finished pulp. For this purpose it is desirable to incorporate part of the bleach with the pulp in the first instance and then feed it through one of these rotary bleachers into a washer of any desired construction and which may as indicated in Fig. 1 comprise a washer chute 20 coöperating with the discharge flange of the bleacher. The desired quantities of water may be added by one or more water pipes such as 21, so that any soluble or readily suspended material is removed with the water which passes out through the open ended perforated washer cylinder 23 revolved by the shaft 22. The pulp may thus be dried by the removal of the desired proportion of water and may then be removed from the cylinder and discharged into the feed chute 26 or any other suitable feeding device communicating with the feed hopper 27 of a second similar rotary bleacher unit which may be oppositely inclined and arranged with advantage beside the first bleacher on substantially the same level, so that its discharge end is adjacent the feed end of the first unit. Suitable bleaching liquor may be supplied through the pipe 24 and the mixture thoroughly incorporated and fed into and through this second bleacher 31 having similar construction and operation. The thoroughly bleached material may be discharged through the flange 19 into the chute 35 of any suitable washer or conveyer device 36 for further treatment or utilization. In this way the entire bleaching operation is continuous and practically automatic so as to require practically no attention from the time the continuously fed pulp and bleach are supplied

to the first bleacher unit until the material is discharged from the second or final bleacher.

This invention has been described in connection with a number of illustrative embodiments, forms, proportions, materials, parts and arrangements, to the details of which it is not of course limited, since what is claimed as new and what is desired to be secured by Letters Patent is set forth in the appended claims:

1. In fiber pulp bleaching apparatus, a large diameter rotary elongated inclined bleacher having spaced partitions forming a number of communicating chambers therein, internally projecting agitating and mixing devices in said bleacher including radially arranged bucket ribs, feeding means coöperating with the feed end of said bleacher, a reduced axially arranged discharge on the discharge end of said bleacher, a continuous washer device receiving the bleached material from said bleacher to wash and partly dry the same, and a second elongated rotary bleacher connected to said washer to receive material therefrom and arranged adjacent and substantially alongside the first bleacher and inclined in the opposite direction to discharge the bleached material adjacent the feed end of said first bleacher.
2. In fiber bleaching apparatus, a large diameter rotary elongated inclined bleacher having spaced partitions forming a number of communicating chambers therein, feeding means coöperating with the feed end of said bleacher, a reduced axially arranged discharge on the discharge end of said bleacher, a continuous washer device receiving the bleached material from said bleacher to wash and partly dry the same, and a second elongated rotary bleacher connected to said washer to receive material therefrom and arranged adjacent the first bleacher and inclined in the opposite direction to discharge the bleached material adjacent the feed end of said first bleacher.
3. In fiber bleaching apparatus, a large

diameter rotary elongated bleacher having a substantially cylindrical form and provided with internally projecting agitating 50 and mixing devices adjacent its feed end, means to continuously feed into said bleacher a mixture of fibrous material and bleach, a continuous washing device receiving the bleached material from said 55 bleacher to wash and partly dry the same, and a second elongated rotary bleacher connected to said washer to receive bleach and material from said washer and arranged substantially alongside the first bleacher to 60 discharge the bleached material adjacent the feed end of said first bleacher.

4. In fiber bleaching apparatus, a large diameter rotary elongated bleacher having a substantially cylindrical form, means to 65 feed into said bleacher a mixture of fibrous material and bleach, a washing device receiving the bleached material from said bleacher to wash and partly dry the same, and a second elongated rotary bleacher connected to said washer to receive bleach and material from said washing device.

5. In fiber bleaching apparatus, a large diameter rotary bleacher provided with internally projecting agitating mixing devices, 75 means to continuously feed into said bleacher fibrous material and bleach, a washing device receiving the bleached material from said bleacher, and a second large diameter rotary bleacher connected to said 80 washing device to receive material therefrom.

6. In fiber bleaching apparatus, a rotary elongated bleacher, means to feed fibrous material and bleach into said bleacher, a 85 washing device receiving the bleached material from said bleacher to wash the same and a second elongated rotary bleacher to receive the material from said washing device.
